UNITED STATES PATENT OFFICE.

EDWARD ERMOLD, OF NEW YORK, N. Y.

BOTTLE-LABELING MACHINE.

1,308,280.

Specification of Letters Patent.

Patented July 1, 1919.

Application filed November 20, 1917. Serial No. 203,030.

To all whom it may concern:

Be it known that I, EDWARD ERMOLD, a citizen of the United States of America, and a resident of New York, in the county of 5 New York and State of New York, have invented certain new and useful Improvements in Bottle-Labeling Machines, of which the following is a specification.

This invention relates to improvements in 10 machines for applying labels to bottles and the objects of the invention are to provide a simple, economical and effective bottle labeling machine, capable of labeling a very large number of bottles at a uniform rate of 15 speed without interruption. Further objects of the invention are to improve upon the bottle conveyer means so that the bottles are delivered from the machine in an upright position. Further objects of the invention are to improve upon the construction, movement, and operation of the pickers 20 for removing the labels from the label boxes. Further objects of the invention are to improve upon the label boxes and their 25 followers, so that several thousand labels can be held in each label box so as to permit the withdrawal of the labels one at a time, by the pickers without interruption. Further objects of the invention are to improve upon 30 the presser fingers and their operation. Further objects of the invention will hereinafter appear, and while the invention is to be described with particular reference to the details of construction, the same is not to be 35 considered as limited thereto, as many changes can be made and still fall within the scope of the invention set forth in the following claims.

Referring to the drawings:

40 Figure 1, is a front view of a bottle labeling machine made in accordance with the invention, for the purpose of illustration, some of the parts are shown broken away and others omitted.

45 Fig. 2 is a side view of the right hand side of the machine, for the purpose of illustration, some of the parts are shown broken away and others omitted.

50 Fig. 3 is a side view of the left hand side of the machine, for the purpose of illustration, some of the parts are shown broken away and others omitted.

55 Fig. 4 is a top view of the machine, for the purpose of illustration, some of the parts are shown broken away and others omitted.

Fig. 5 is a sectional view through the cen-

ter of the machine, showing the conveyer means, for the purpose of illustration, some of the parts are shown broken away and others omitted.

Fig. 6 is a sectional view through the center of the machine, showing the upper part of the machine, for the purpose of illustration, some of the parts are shown broken away and others omitted.

Fig. 7 is a detail perspective view of one end of the presser carriage.

Fig. 8 is a detail perspective view of the presser carriage switch.

Fig. 9 is a detail view partly in cross-section of the presser carriage switch.

Fig. 10 is a detail perspective view of the pickers.

Referring to the drawing, 1 and 2 designate suitable side standards comprising the 75 frame of the machine upon which the different operating parts are mounted. Suitably journaled in the side standards are front and rear shafts, 3 and 4, to each of which is secured two sprocket wheels, 5 and 6, positioned against the inner faces of the side standards. The sprocket wheels, 5 and 6, are each respectively connected by means of suitable sprocket chains 7, one on each side of the machine, the same being connected at intervals to the ends of transverse lag-bars 8, in the present instance six in number. Each lag-bar is provided with a plurality of conveyer-fingers 9, secured thereto in pairs; in the present instance each lag-bar has six pairs of conveyer-fingers, spaced at intervals transversely across the machine.

Suitably secured to the side standards at the front end of the machine is a receiving-tray 10, which has a series of tray-partitions 11, secured thereto between the longitudinal rows of conveyer-fingers. The adjacent sides of the outer ends of adjacent tray-partitions are suitably shaped to hold, in an inclined position, a bottle placed therebetween. In order to keep the bottle centered, between the adjacent tray-partitions, suitably grooved rests 12, each secured at one end to the receiving-tray are provided therebetween, the longitudinal rows of conveyer-fingers in each instance being arranged to pass on either side of the grooved rest to engage the bottle. In the present instance the receiving-tray is arranged to hold at any one time six bottles, one for each of the longitudinal rows of conveyer-fingers;

as each transverse row of conveyer-fingers moves forward, in the operation of the machine, six more bottles can be inserted in the receiving-tray to be engaged by the next 5 succeeding transverse row of conveyer-fingers and so on continuously.

Between each longitudinal row of conveyer-fingers is arranged a suitable slide or track 13, upon which the bottom of the bottle slides, on its passage through the machine, as the same is moved forward by the conveyer-fingers. Each track 13 is secured at one end to a cross-bar 14, and at the other end to a discharging-tray 15. In the present instance each track 13 is bent, as shown 10 in Fig. 6, so as to present a curved guide for the bottle from the time it leaves the receiving-tray, until it assumes a vertical position. After the bottle assumes a vertical position 15 the slide continues for a certain distance to remain horizontal while the bottle is being labeled, the conveyer-fingers continuing to move the bottle along the slide 13, until it reaches the discharging-tray 15, moving 20 ahead any bottle that may have preceded it 25 on the discharging-tray. In order to prevent the bottle being turned over as it is moved on to the discharging-tray by the angular downward movement of the conveyer-fingers, as they pass around the sprocket 30 wheels 5, the discharging end of each of the slides 13, is bent upward. This forcing of the bottle uphill just preceding its movement on to the discharging-tray, where the 35 slide again assumes a horizontal position, permits the bottle to lean backward against the conveyer-fingers, thereby preventing the bottle being tipped over forward as the conveyer-fingers slide down the side of the bottle, in a forward angular direction, as they 40 start to pass around the sprocket wheels 5.

In the present instance the discharging-tray 15, has a series of discharging-partitions 16, secured thereto between the longitudinal rows of conveyer-fingers. The inner 45 end of each of the discharging-partitions is preferably grooved so as to removably hold one end of an intermediate partition 17. The other ends of the intermediate-partitions are 50 removably held in suitable slotted pins 18, secured to wiper-uprights 19, the upper ends of which are secured to a cross bar 20, secured to the side standards. The lower end of each of the wiper-uprights is secured to 55 one end of a bolt 21, the other end of which is secured to an angle-bar 22. The discharging-partitions together with their respective intermediate-partitions, between the longitudinal rows of conveyer-fingers on each 60 side of the slides, keeps the bottles in alignment on their passage through the machine and prevents them from moving sidewise off their respective slides.

In order to keep the conveyer-fingers in a 65 vertical position, after they have taken a

bottle from the receiving-tray, and in order to keep the sprocket-chains 7 from sagging downward, each lag-bar 8 is provided with a shoe 23, intermediate of its length which is adapted to engage a guide plate 24, as clearly 70 shown in Fig. 5, mounted on the shaft 3, at one end and upon a shaft 25, at the other end.

The upper part of the side standards are each provided, adjacent their front ends, 75 with an inclined slot 26, which is nearly vertical, that constitutes a runway for one side of a transversely positioned picker frame 27, provided with suitable cross-heads 28, that 80 slidably engage the slots 26.

In the present instance the picker-frame 27, is pivoted at each end to one of the cross-heads 28, by means of a suitable bearing-pin 29, which is mounted in each instance, upon a short upright member 30, one of which is 85 secured to each end of the picker-frame.

The picker-frame 27 is provided with a plurality of downwardly extending picker-supports 31, secured at their upper ends to the picker-frame, between the longitudinal 90 rows of conveyer-fingers. The adjacent sides of adjacent picker-supports are each provided with a picker 32, hinged thereto, in each instance, by means of a suitable pivot pin 33, mounted in suitable bearing lugs 34 95 and 35, secured respectively to the picker-support and picker, a suitable spring 36, being mounted in each instance, on the pivot pin 33, to keep the picker in closed position against the face of its respective picker-support. 100

Each cross-head 28, of the picker-frame is pivotally connected to one end of an adjusting link 37, the other end of which is secured to the upper end of a reciprocating link 38. 105 The lower end of the reciprocating links are secured respectively to the outer ends of levers 39 and 40, which are secured to the opposite ends of a shaft 41, the inner ends of the levers 39 and 40, being connected by 110 means of a weight-bar 42, secured thereto which acts to counter-balance the weight of the picker-frame.

The picker-frame 27 carrying the pickers 32 is reciprocated up and down and controlled in its movements by means of two cams 43 and 44, secured to one side of a large gear 45, mounted on the shaft 4. The cam 44 is arranged to engage a roller 46, mounted on a pin 47, to which is also mounted the ends of two links 48 and 49, the other ends of the links 48 and 49, being mounted respectively on the end of a shaft 50, and the end of the shaft 41. The cam 43 is arranged to engage a roller 51 mounted on a pin 52, secured to one end of a link 53, the other end of which is loosely mounted on the end of the shaft 41. The upper end of the link 53, is secured to one end of a rod 54, the other end of which passes through an eye- 125 130

bolt 55, secured to the upper end of the link 49. The free end of the rod 54, is provided with a spring 56, which acts to keep the rollers 51 and 46, in engagement with their respective cams 43 and 44.

When in the operation of the machine the picker-frame 27, by the action of the cams 43 and 44, reaches its upper limit, as shown in Figs. 2, 3, and 6, a roller 57, secured to one of the upright members 30, is arranged to engage the slotted end of a short lever 58, secured to a shaft 59, having at its outer end a short lever 60. The outer end of the lever 60, is provided with a pin 61, which engages a right angle slot 62, in one end of a lever 63, the other end of which is pivoted to one end of a bell crank lever 64, loosely mounted on one end of the shaft 25. The other end of the bell crank lever 64, is provided with a roller 65, which engages a cam slot 66, in a cam 67, which acts, when the roller 57 enters the slotted end of the lever 58, to force the same outward, thereby swinging the picker-frame 27 about the bearing-pins 29, to force the pickers 32 against their respective label boxes 68 and 69. The cross-heads 28 are each provided with a stud 70, having a spring 71, which acts together with a spring 72, one end of which is secured to the extended end of the lever 58, and the other end to a stud 73, secured to the frame, to return the picker-frame to the position shown in Fig. 6. The lever 58 is provided with an extension 74, which loosely engages a bolt 75, which acts to limit the outward movement of the slotted end of the lever 58.

When in the operation of the machine it is not desired to force the picker-frame inward against the label boxes, a bell-crank lever 76, pivoted to the end of the shaft 59, is operated, as shown in Fig. 3, to permit a spring 77, one end of which is secured to the lever 63, and the other end to the frame, to draw the lever into inoperative position in the slot 62, which permits the lever 63 to be moved up and down by the action of the cam groove 66, without operating the picker-frame to force the same into engagement with the label boxes.

In the present instance it will be seen that the label boxes 68 and 69, are held in a suitable label-frame 78, there being one set of label boxes for each set of pickers. The label-frame 78 is set so as to hold the end labels in the label boxes, on a radial plane which passes through the pivot-pins 29, so as to present the end labels to the pickers as the pickers are forced inward about the pivot-pins 29, as before described.

In the present instance the label boxes 68 are arranged to hold neck labels 79, and the label boxes 69, to hold body labels 80, each set of label boxes being made of sufficient length to hold several thousand labels.

Each corresponding neck and body label box is respectively provided with a follower plate 81, and 82, which are pivoted respectively to one end of links 83 and 84, the other ends of which are pivoted to the opposite ends of a lever 85, pivoted midway of its length to a rocker-arm 86, by means of a pin 87. The rocker-arms 86, are each loosely mounted at one end upon a shaft 88, so that the entire weight of the other end of the rocker-arm will act in each instance to force the neck and body labels against the fingers 89 and 90, by forcing the follower plates 81 and 82, against the top of the piles of labels.

In order to insure the pickers removing only one label from each label box every time the picker-frame forces the pickers inward, the outer end of each rocker-arm 86, is made with a segmental edge 91, which is arranged to engage in each instance a friction plunger 92, having a stud 93, loosely mounted on a spring 94, suitably secured to a plunger frame 95, which is secured to a shaft 96, loosely mounted in the ends of brackets 97, secured to the frame. The friction plungers 92 are each brought into and out of frictional engagement with their respective rocker-arms 86, by means of a peripheral cam 98, on the periphery of the cam 67, which is arranged to engage a roller 99 on the end of a lever 100 the other end of which is pivoted to the frame. The lever 100 is connected midway of its length to one end of a rod 101, the other end of which is connected to an adjusting link 102, secured to one end of an arm 103, secured to one end of the shaft 96.

From the above description it will be seen that when in the operation of the machine the picker-frame has reached its upper position and just preceding the time the cam groove 66 acts to force the pickers inward against their respective label boxes, the roller 99 is riding on a low portion 104, of the cam 98, so as to relieve the pressure of the friction plungers 92, against their respective rocker-arms 86, which permits the weight of the rocker-arms to bear against their respective piles of labels. The roller 99 rides on the low portion 104, of the cam 98, while the cam groove 66 acts to force the pickers inward against their respective label boxes which acts to force the labels backward against the weight of the rocker-arms raising them slightly. In the further operation of the machine and before the cam groove 66, operates to withdraw the pickers from in contact with their respective label boxes, the roller 99 rides up on a high portion 105 of the cam 66 so as to force all of the friction plungers 92 into engagement with their respective rocker-arms holding the same in their raised position. The rocker-arms are held in raised position by

the cam 98 and thereby prevented from exerting any pressure upon their respective piles of labels until the cam groove 66 has acted to withdraw the pickers from in contact with their respective label boxes. The action of the cam 98, to relieve the pressure on the piles of labels permits of the pickers which have previously been coated with glue each to withdraw a single label from each 10 label box without tearing or missing a label.

In the further operation of the machine, after the pickers have removed their respective labels from the label boxes, the roller 99 enters another low portion 106 on the cam 98, which again relieves the pressure of the friction plungers 92, against their respective rocker-arms permitting them to move downward to force the labels together in the label boxes. After the labels are forced together 20 in the label boxes the roller 99 in the further operation of the machine rises on a high part 107, of the cam 98, to lock the rocker-arms in their lower position, until just previous to the time the cam groove 66 acts to force 25 the pickers inward against the label boxes, when the roller 99 enters the low portion 104, of the cam 98, to unlock the rocker-arms as before described.

When in the operation of the machine the 30 picker-frame 27 is moved upward and with it the pickers 32, as before described, the face of the pickers are arranged to be engaged by a paste roller 108, which extends transversely across the machine. The ends 35 of the paste roller extend through suitable slots in the frame, the same being rotatably supported at one end, to one end of a lever 109, the other end of which is pivoted to the frame. The other end of the paste roller is 40 rotatably mounted on one end of a bell crank lever 110, also pivoted to the frame, the other end of the bell crank lever 110 being pivoted to one end of a rod 111, to the other end of which is mounted a roller 112, which 45 is also mounted on the end of an arm 113, the other end of which is mounted on the shaft 25, as shown in dotted lines in Figs. 3 and 6. The roller 112 is arranged to engage a cam 114, on the back of the cam 67, which 50 acts to force the paste roller 108 out into engagement with the face of the pickers 32, every time the pickers, in the operation of the machine, move upward, so as to give the face of the pickers a coating of glue, after 55 which the cam 114 acts to withdraw the paste roller so that it will not engage the pickers on their downward movement.

When in the operation of the machine the 60 paste roller 108 is moved inward, as before described, it is arranged to engage a paste supply roller 115, the ends of which are mounted in a paste tank 116, secured to the frame. One end of the paste supply roller extends out through one side of the frame 65 and has adjustably secured thereto a remov-

able sprocket 117, which engages a sprocket chain 118, which also engages an idler sprocket 119, and a driving sprocket 120, secured to one end of the shaft 3. The idler sprocket 119, is suitably mounted on an adjusting arm 121, which permits of the adjustment of the sprocket chain 118 to fit various sized sprockets 117, which can be substituted to drive the paste supply roller at different speeds. The paste supply roller 70 115 is provided at one end with a gear 122, which is arranged to mesh with a similar gear, not shown, secured to the adjacent end of the paste roller 108, when in the operation of the machine the paste roller is forced inward out of the path of the pickers, by the action of the cam 114.

The sprocket 117 has a flanged portion adapted to engage a lever 123, pivoted at one end to the frame and locked at the other end, which can be operated to remove the sprocket 117, so that the paste tank 116, with the paste supply roller can be removed from the machine.

When in the operation of the machine the 90 pickers 37 move downward, each with a neck and body label adhering thereto, into the path of movement of their respective bottles carried by their respective conveyer-fingers, each set of labels as they come in 95 contact with their respective bottles are arranged to be engaged by one of a set of presser-fingers 124 and 125, mounted on a presser-rod 126. The presser-rods are secured at their upper ends to a presser-carriage 127, the ends of which are slidably mounted on rollers 128 supported in suitable guideways 129 in the frame.

The presser carriage 127 is secured at one end to one end of a universally pivoted arm 130, the other end of which is pivoted to one end of a lever 131, the other end of which is mounted on the shaft 25. The lever 131 has secured thereto intermediate of its length an arm 132, having at its outer end a roller 133, which engages a cam groove 134, formed on the back of the gear 45, which acts to move the presser carriage back and forth in a longitudinal direction along the guideways 129. The other end of the 110 presser carriage is also secured to one end of a universally pivoted arm 135, the other end of which is pivoted to one end of a lever 136, the other end of which is mounted on the shaft 25.

The presser carriage 127 near the end of its backward longitudinal movement is arranged to be moved transversely, to bring the presser fingers out of the path of movement of the bottles, this movement is accomplished by means of a roller 137, secured to the bottom of the presser carriage, which is arranged to engage a two way switch 138, secured to the underside of the rearward end of one of the guideways 129. The switch 138 120

is provided with a dog 139, pivoted near its center and pointed at both ends. The inner end of the dog 139, is provided with a pin 140, which projects through a slot 141, in 5 the bottom of the switch, to which is secured a spring 142, also secured to a small projection 143 on the switch. The spring 142 acts to keep the inner end of the dog 139 drawn inward as shown in Fig. 8, so that the presser carriage will not move transversely on its 10 forward movement until the roller 137 engages the outwardly curved portion 144 of the switch, which acts to move the presser carriage at the end of its forward movement 15 outward to disengage the presser fingers from their respective bottles. On the backward movement of the presser carriage the roller 137 passes on the other side of the dog 139, and engages the inwardly curved portion 20 145 of the switch, which acts to move the presser carriage inward to bring the presser fingers again into position to engage the bottles.

By referring to Figs. 6 and 7, it will be 25 seen that the presser fingers 124 and 125 are normally pressed outward by means of suitable coiled springs 146, which are compressed when the presser carriage forces the presser fingers into engagement with the bottles to 30 hold the labels thereon. As the bottles move forward after the labels thereon have been engaged by the presser fingers, the cam groove 134 acts to move the presser carriage a little faster than the speed of the bottles, 35 so as to slightly relieve the tension on the presser finger springs 146, which pressure is finally entirely relieved by the time the switch 138 acts to force the presser fingers out of the way of the bottles.

40 The wiper-uprights 19 are each provided with neck and body label wipers 147 and 148, preferably made of rubber, which act to wipe the labels on the bottles after they have been engaged by the presser fingers.

45 In the present instance the machine is driven by means of an electric motor 149, mounted on top of the frame, which is connected by means of a belt 150, with a pulley 151, suitably supported on the frame and 50 provided with a small gear 152, which engages a gear 153, having secured thereto a gear 154, which engages the large gear 45. The large gear 45, has secured thereto a sprocket wheel 155, which is connected to a 55 sprocket wheel 156, mounted on the shaft 3, by means of a sprocket chain 157. The pulley 151 is shifted into and out of operation by means of a suitable lever 158, which is connected to a shift bar 159, which runs 60 across the face of the machine.

The operation of the machine is as follows: Bottles to be labeled, in the present instance six in number, are placed in the receiving tray 10, from which they are almost 65 immediately removed by the conveyer fin-

gers 9. The picker frame acting in the meantime to move the pickers 32 upward past the paste roller 108, which is forced outward to coat the pickers with a coating of glue. The picker frame then moves to its 70 uppermost position, in which position the pickers are forced inward to engage the label boxes 68 and 69 extracting therefrom in each instance a neck label 79 and a body label 80. The picker frame together with the pickers 75 each carrying neck and body labels then moves downward, the paste roller 108 in the meantime having been withdrawn, to its lowermost position, holding each set of labels across the path of movement of its respective 80 bottle. The bottles in the meantime having continued to move forward engage the labels, and as they do the presser carriage forces the presser fingers each into engagement with the set of labels for its respective 85 bottle. The bottles continue to move forward together with the presser fingers gripping the labels past the neck and body wipers 147 and 148, which act in each instance to press the labels on the bottle, the 90 pickers in the meantime having moved upward out of the way. After the bottles have passed the wipers the presser carriage moves the presser fingers transversely out of the path of movement of the bottles which continue to slide along their respective slides 13, 95 as before described, until they reach the discharging tray 15.

As soon as one set of six bottles has been placed upon the receiving tray and has 100 moved out of the way which is almost immediately, another set of six bottles is placed in the receiving tray, the different parts of the machine operating as before described, to continually label the bottles as they pass 105 continuously through the machine.

What I claim is:

1. A labeling machine comprising a receiving tray arranged to hold the article to be labeled in a horizontal position, a discharging tray arranged to receive the labeled article in an upright position, a slide connecting said receiving tray, with said discharging tray, said slide being curved upward to a horizontal position adjacent said receiving tray, said slide sloping upward from a horizontal position adjacent said discharging tray, a conveyer for moving the article to be labeled from the receiving tray along the curved portion of said slide to an 110 upright position in which position it remains while the conveyer moves it, along the horizontal portion of said guide and the upward slope thereof, to the discharging tray, and labeling means operated in definite relation 115 to the conveyer to apply labels to the articles in the course of their movement along the slide.

2. A labeling machine comprising a receiving tray arranged to hold the articles to be

labeled in a horizontal position, a discharging tray arranged to receive the labeled article in an upright position, a slide connecting said receiving tray with said discharging tray, a continuously driven endless conveyer arranged to move the article to be labeled along said slide from the receiving tray to the discharging tray, said slide being arranged to extend upward adjacent the discharging tray to prevent the labeled article being overturned as it is moved to the discharging tray, and labeling means operated in definite relation to the conveyer to apply labels to the articles in the course of their movement along the slide.

3. A labeling machine comprising a receiving tray arranged to hold the article to be labeled in a horizontal position, a discharging tray arranged to receive the labeled article in an upright position, a slide connecting said receiving tray with said discharging tray, a continuously driven endless conveyer arranged to move the article to be labeled along said slide from the receiving tray to the discharging tray, said slide being arranged to extend upward, as the conveyer moves downward, out of engagement with the labeled article to prevent the labeled article being overturned, as it is released from engagement with the conveyer, and labeling means operated in definite relation to the conveyer to apply labels to the articles in the course of their movement along the slide.

4. A labeling machine comprising a receiving tray arranged to hold a plurality of articles to be labeled in a horizontal position, a discharging tray arranged to receive the labeled articles in an upright position, slides connecting said receiving tray with said discharging tray, one for each article to be labeled, a continuously driven endless conveyer arranged to move the articles to be labeled along said slides from the receiving tray to the discharging tray, a plurality of partitions arranged between said slides to keep the articles to be labeled in position on said slides, and labeling means operated in definite relation to the conveyer to apply labels to the articles in the course of their movement along the slide.

5. A labeling machine comprising in combination, a conveyer for moving articles to be labeled through the machine, a picker frame provided with a plurality of pickers, a plurality of label boxes, means for reciprocating said picker frame, means for oscillating said picker frame, to force said pickers into engagement with said label boxes to remove labels therefrom, and means for applying to the articles, labels carried by said pickers.

6. A labeling machine comprising in combination, a conveyer for moving articles to be labeled through the machine past a point where labels are applied, a picker frame

provided with a plurality of pickers, means for reciprocating said picker frame up and down, a plurality of label boxes situated near the upper limit of movement of said picker frame, means for oscillating said picker frame to force said pickers into engagement with said label boxes, to remove labels therefrom at the upper limit of movement of said picker frame, and means for applying to the articles, labels carried by said pickers.

7. A labeling machine comprising in combination, a conveyer for moving articles to be labeled through the machine past a point where labels are applied, a reciprocating and oscillating picker frame provided with a plurality of pickers, a plurality of label boxes, means for reciprocating said picker frame up and down, means for oscillating said picker frame on its upward movement, to force said pickers into engagement with said label boxes to remove labels therefrom, and means for applying to the articles, labels carried by said pickers.

8. A labeling machine comprising in combination, a receiving tray and a delivery tray, a conveyer for moving articles to be labeled through the machine from the receiving tray to the delivery tray, a picker frame provided with pickers, a plurality of label boxes, arranged to be engaged by said pickers, weighted means arranged to bear upon the labels in said label boxes, means for locking said weighted means when the labels have been pushed inward by the pickers, to relieve the pressure of the weighted means on the labels, while the end labels are being withdrawn by the pickers, and means for applying to the articles, labels carried by said pickers.

9. A labeling machine comprising in combination, a receiving tray and a delivery tray, a conveyer for moving articles to be labeled through the machine from the receiving tray to the delivery tray, a picker frame provided with pickers, a plurality of label boxes arranged to be engaged by said pickers, weighted means arranged to bear upon the labels in said label boxes, means for locking said weighted means, when the labels have been pushed inward by the pickers, to relieve the pressure of the weighted means on the labels while the end labels are being withdrawn by the pickers, means for unlocking said weighted means after the end labels have been withdrawn by the pickers to permit the pressure of the weighted means to force the labels together, and means for applying to the articles, labels carried by said pickers.

10. A labeling machine comprising in combination, a receiving tray and a delivery tray, a conveyer for moving articles to be labeled through the machine from the receiving tray to the delivery tray past a

- point where labels are applied, a picker frame provided with pickers, a plurality of label boxes arranged to be engaged by said pickers, weighted means arranged to bear upon the labels in said label boxes, means for locking said weighted means when the labels have been pushed inward by the pickers, to relieve the pressure of the weighted means on the labels while the end labels are being withdrawn by the pickers, means for unlocking said weighted means after the end labels have been withdrawn by the pickers to permit the pressure of the weighted means to force the labels together, means for locking said weighted means after the labels have been forced together, and means for applying to the articles, labels carried by said pickers.
11. A labeling machine comprising in combination, a receiving tray and a delivery tray, a conveyer for moving articles to be labeled through the machine from the receiving tray to the delivery tray past a point where labels are applied, a picker frame provided with pickers, a plurality of label boxes arranged to be engaged by said pickers, weighted means arranged to bear upon the labels in said label boxes, means for locking said weighted means when the labels have been pushed inward by the pickers, to relieve the pressure of the weighted means on the labels while the end labels are being withdrawn by the pickers, means for unlocking said weighted means after the end labels have been withdrawn by the pickers to permit the pressure of the weighted means to force the labels together, means for locking said weighted means after the labels have been forced together, means for unlocking said weighted means just previous to the time the end labels are engaged by the pickers, and means for applying to the articles, labels carried by said pickers.
12. A labeling machine comprising in combination, a receiving tray and a delivery tray, a conveyer for moving articles to be labeled through the machine from the receiving tray to the delivery tray past a point where labels are applied, a picker frame provided with pickers, a plurality of label boxes arranged to be engaged by said pickers, a pivotally mounted rocker arm arranged to bear upon the labels in said label boxes, means for locking said rocker arm, when the labels have been pushed inward by the pickers to relieve the pressure of the rocker arm on the labels while the end labels are being withdrawn by the pickers, and means for applying to the articles, labels carried by said pickers.
13. A labeling machine comprising in combination, a receiving tray and a delivery tray, a conveyer for moving articles to be labeled through the machine from the receiving tray to the delivery tray past a point where labels are applied, a picker frame provided with pickers, a plurality of label boxes arranged to be engaged by said pickers, a pivotally mounted rocker arm arranged to bear upon the labels in said label boxes, means for locking said rocker arm, when the labels have been pushed inward by the pickers, to relieve the pressure of the rocker arm on the labels while the end labels are being withdrawn by the pickers, and means for applying to the articles, labels carried by said pickers.
14. A labeling machine comprising in combination, a receiving tray and a delivery tray, a conveyer for moving articles to be labeled through the machine from the receiving tray to the delivery tray past a point where labels are applied, a picker frame provided with pickers, a plurality of label boxes arranged to be engaged by said pickers, a pivotally mounted rocker arm arranged to bear upon the labels in said label boxes, means for locking said rocker arm, when the labels have been pushed inward by the pickers, to relieve the pressure of the rocker arm on the labels while the end labels are being withdrawn by the pickers, means for unlocking said rocker arm, after the end labels have been withdrawn by the pickers, to permit the pressure of the rocker arm to force the labels together, and means for applying to the articles, labels carried by said pickers.
15. A labeling machine comprising in combination, a receiving tray and a delivery tray, a conveyer for moving articles to be labeled through the machine from the receiving tray to the delivery tray past a point where labels are applied, a picker frame provided with pickers, a plurality of label boxes arranged to be engaged by said pickers, a pivotally mounted rocker arm arranged to bear upon the labels in said label boxes, means for locking said rocker arm, when the labels have been pushed inward by the pickers, to relieve the pressure of the rocker arm on the labels while the end labels are being withdrawn by the pickers, means for unlocking said rocker arm, after the end labels have been withdrawn by the pickers, to permit of the pressure of the rocker arm to force the labels together, means for locking said rocker arm after the labels have been forced together, and means for applying to the articles, labels carried by said pickers.
16. A labeling machine comprising in combination, a receiving tray and a delivery tray, a conveyer for moving articles to be

- labeled through the machine from the receiving tray to the delivery tray past a point where labels are applied, a picker frame provided with a plurality of sets of pickers, a plurality of sets of label boxes, a plurality of pivotally mounted rocker arms, one for each set of label boxes, each arranged to bear upon the labels in their respective label boxes, means for locking 5 all of said rocker arms when the labels in the label boxes have been pushed inward by their respective pickers, to relieve the pressure of the rocker arms on their respective labels while the end labels are being withdrawn by the pickers, and means for applying to the articles, labels carried by said pickers.

17. A labeling machine comprising in combination, a receiving tray and a delivery tray, a conveyer for moving articles to be labeled through the machine from the receiving tray to the delivery tray past a point where labels are applied, a picker frame provided with a plurality of sets of pickers, 20 a plurality of sets of label boxes, a plurality of pivotally mounted rocker arms, one for each set of label boxes, each arranged to bear upon the labels in their respective label boxes, and means for locking all of said rocker arms when the labels in the label boxes have been pushed inward by their respective pickers, to relieve the pressure of the rocker arms on their respective labels while the end labels are being withdrawn by the pickers, 25 means for unlocking all of said rocker arms after the end labels have been withdrawn by the pickers, to permit the pressure of the rocker arms to force their respective labels together, means for locking said rocker arms after the labels have been forced together, means 30 for unlocking said rocker arms just previous to the time the end labels are engaged by the pickers, and means for applying to the articles, labels carried by said pickers.

18. A labeling machine comprising in combination, a receiving tray and a delivery tray, a conveyer for moving articles to be labeled through the machine from the receiving tray to the delivery tray past a point where labels are applied, a picker frame provided with a plurality of sets of pickers, a plurality of sets of label boxes, a plurality of pivotally mounted rocker arms, 45 one for each set of label boxes, each arranged to bear upon the labels in their respective label boxes, and means for locking all of said rocker arms when the labels in the label boxes have been pushed inward by their respective pickers, to relieve the pressure of the rocker arms on their respective labels while the end labels are being withdrawn by the pickers, means for unlocking all of said rocker arms after the end labels have 50 been withdrawn by the pickers, to permit the pressure of the rocker arms to force their respective labels together, means for locking said rocker arms after the labels have been forced together, and means for applying to the articles, labels carried by said pickers.

ing to the articles, labels carried by said pickers.

19. A labeling machine comprising in combination, a receiving tray and a delivery tray, a conveyer for moving articles to be labeled through the machine from the receiving tray to the delivery tray past a point where labels are applied, a picker frame provided with a plurality of sets of pickers, a plurality of sets of label boxes, a plurality of pivotally mounted rocker arms, 70 one for each set of label boxes, each arranged to bear upon the labels in their respective label boxes, and means for locking all of said rocker arms when the labels in the label boxes have been pushed inward by their respective pickers, to relieve the pressure of the rocker arms on their respective labels while the end labels are being withdrawn by the pickers, means for unlocking all of said rocker arms after the end 75 labels have been withdrawn by the pickers, to permit the pressure of the rocker arms to force their respective labels together, means for locking said rocker arms after the labels have been forced together, means 80 for unlocking said rocker arms just previous to the time the end labels are engaged by the pickers, and means for applying to the articles, labels carried by said pickers.

20. A labeling machine comprising in combination, a continuously driven endless conveyer arranged to convey an article to be labeled, pickers arranged to carry labels into the path of movement of said article to be labeled, presser fingers arranged to engage the label on said article to be labeled, means for keeping said presser fingers in engagement with the article to be labeled, during the forward movement thereof, means for moving said presser fingers out of the path of movement of said article to be labeled, and means for relieving the pressure of said presser fingers against the article to be labeled, previous to the time the presser fingers are moved out of the path of movement of the article to be labeled.

21. A labeling machine comprising in combination, a continuously driven endless conveyer arranged to convey a plurality of articles to be labeled, a plurality of pickers arranged to carry a plurality of sets of labels into the path of movement of said articles to be labeled, a plurality of presser fingers arranged to engage the sets of labels on the articles to be labeled, during the forward movement thereof, means for moving said presser fingers out of the path of movement of said articles to be labeled, and means for relieving the pressure of said presser fingers against the articles to be labeled, previous to the time the presser fingers are moved out of the path of movement of the articles to be labeled.

22. A labeling machine comprising in combination, a reciprocating and oscillating picker frame having pickers, a paste roller and a label box, means for reciprocating said 5 picker frame up and down, means for forcing said paste roller into engagement with said pickers on the upward movement of said picker frame, and means for oscillating said picker frame at the end of its upward

movement, to force the pickers into engagement with said label box.

In testimony whereof I have signed this specification in the presence of two subscribing witnesses.

EDWARD ERMOLD.
